US0D1114036S

(12) **United States Design Patent** (10) **Patent No.:** **US D1,114,036 S**
(45) **Date of Patent:** **** Feb. 17, 2026**

(54) **PROJECTOR**

(71) Applicant: **Yanfang Lai**, Shenzhen (CN)

(72) Inventor: **Yanfang Lai**, Shenzhen (CN)

(**) Term: **15 Years**

(21) Appl. No.: **29/938,288**

(22) Filed: **Apr. 19, 2024**

(51) **LOC (15) Cl.** **16-02**

(52) **U.S. Cl.**

USPC **D16/229**

(58) **Field of Classification Search**

USPC D16/221-231, 234, 235, 242, 245;
D21/514; D26/93, 94, 98, 99, 106, 108

CPC G03B 21/16; G03B 21/145; G03B 21/32;
G03B 21/14; G03B 21/00; G03B 21/001;

(57) **CLAIM**

The ornamental design for a projector, as shown and described.

DESCRIPTION

FIG. 1 is a front, right and top perspective view of a projector, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of area "9" in FIG. 1;

FIG. 10 is an enlarged view of area "10" in FIG. 1; and,

FIG. 11 is an enlarged view of area "11" in FIG. 2.

The broken lines shown in the drawings illustrate portions of the projector and forms no part of the claimed design. The dot dash broken lines in FIGS. 1, 2 and 9-11 show the boundary of the enlarged views and forms no part of the claimed design.

1 Claim, 11 Drawing Sheets
